EXERCISING HORSE

Myles John Burke, Jersey City, N. J.

Application June 12, 1940, Serial No. 340,001

2 Claims. (Cl. 128—49)

This invention relates to new and useful improvements in an exercising horse.

The invention proposes an exercising horse which is characterized by a narrow frame resembling the frame of a bicycle and provided with a seat and handle bars, and a mechanism for oscillating and moving the seat and handle bars in a certain path for exercising a person.

The invention proposes to so arrange the seat and handle bars that the exercising horse may be used in different ways to exercise different muscles of the body. It is proposed that the exercising horse be ridden as a motorcycle, as a horse with the legs straddling the seat, or with the legs to one side of the seat only. Furthermore, it is proposed that the parts be so arranged that a person may stand on the ground and wrestle with moving parts of the horse for exercising purposes.

Still further the invention proposes that the seat be pivotally mounted and that a novel mechanism be provided for oscillating the seat on its pivot. It is also proposed that this mechanism be connected with the handle bars for oscillating same.

The invention also contemplates an arrangement whereby the speed of oscillation of the seat and handle bars may be controlled.

An arrangement is also proposed whereby the amplitude of oscillation of the parts mentioned in the previous paragraph may be controlled.

Another object of the invention resides in the provision of a massaging element arranged to be reciprocated by the mechanism which oscillates the seat and handle bars.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of an exercising horse constructed in accordance with this invention.

Fig. 2 is a vertical sectional view taken on the line 2—2 of Fig. 1.

Fig. 3 is a fragmentary vertical sectional view taken on the line 3—3 of Fig. 1.

Fig. 4 is a fragmentary horizontal sectional view taken on the line 4—4 of Fig. 1.

The exercising horse, in accordance with this invention, includes a narrow frame 10 having a base 11 for resting on the ground 12. The frame

10 is similar to a bicycle frame. It is constructed from a plurality of fittings and pipe or rod sections connected together as a unit. A seat 14 is centrally transversely pivotally mounted by a pintle 15 on a central area of the frame 10 so that when one sits on the seat the legs are at the sides of the frame. The seat 14 has a hollowed out bottom wall 14a from which a stud 17 projects. The pintle 15 engages through this stud and through a stationary support rod 18 which is fixedly mounted on the frame 10. The arrangement is such that the front and back ends of the seat 14 may pivot upwards and downwards about the pivot 15.

15 A bar 19 is centrally transversely pivotally mounted by a pintle 20 on the frame 10 beneath the seat 14. More specifically, the pintle 20 is supported by a bracket 21 which is mounted on a portion of the frame 10. The bar 19 extends forwards and rearwards along the longitudinal length of the seat 14. The bar 19 is formed from two bar sections 19a and 19b which are separate from each other and which extend along the sides of the frame 10, but which function as a unit. The pivot pintle 20 passes through each of the bar sections.

20 A front link 22 is connected between the front of the bar 19 and the front of the seat 14. This front link is also formed from two front link sections 22a and 22b which extend along the sides of the frame 10. At their lower ends these front link sections 22a and 22b are pivotally connected by a pintle 23 to the front ends of the bar sections 19a and 19b, respectively. The upper ends of the front link sections 22a and 22b are connected by a pintle 24 to lugs 25 mounted on the bottom of the seat 14.

25 A rear link 26 is connected between the rear of the bar 19 and the rear of the seat 14. This rear link also comprises a pair of rear link sections 26a and 26b which are pivotally connected by a pintle 27 with the rear ends of the bar sections 19a and 19b. The rear link sections 26a and 26b are pivotally connected at their upper ends by a pintle 28 mounted on a bracket 29 mounted on the bottom of the seat 14.

30 A speed controlled motor driven crank 30 is mounted on the base 11. This crank includes a stationary casing 31 which is fixedly mounted on a bottom portion of the frame 10 and which rotatively supports the crank 30. One end of the crank 30 projects from the casing 31 and is provided with a plain wheel 32 over which a belt 33 engages. The belt 33 extends over a pulley 34 of a manually controllable transmission 35. The

transmission 35 has a driven wheel 36. This wheel 36 is engaged by the belt 37 of an electric motor 38. The motor 38 is mounted on the base 11. A switch 39 is mounted on the frame 10 to the front of the seat 14 by which the motor 38 may be turned on and off. The electrical connections will not be given in this specification as they form no part of the invention. The transmission 35 is provided with a shift lever 35a connected with linkage 35b which is connected with a control handle 35c which may be set to various positions to vary the drive ratio of the transmission. The handle 35c is pivotally mounted by a pintle 35d. A spring clamp 35e holds the handle 35c in its various positions. A guard 40 is engaged over a portion of the belt 33 for safety reasons.

A connector rod 41 is mounted between the crank 30 and the pintle 23. The arrangement is such that when the crank 30 turns the bar 19 will be rocked, and through the medium of the links 22 and 26 the seat 14 will be correspondingly rocked. The transmission 35 controls the speed at which the seat 14 rocks.

A pair of pivotally mounted handle bars 42 is arranged on the front end of the frame 10. These handle bars have a central portion 42a which pass through bearings 43 stationarily mounted on a rod 44 which is mounted on the frame 10. There is a means for operably connecting the crank 30 with the handle bars 42 to oscillate them. This means includes a radially extending arm 45 fixedly mounted on the central portion of the handle bars 42 between the bearings 43. A link 46 has a top pintle bolt 47 engaging one of a series of openings 48 formed in the arm 45. The link 46 extends downwards and pivotally connects with another link 49 which in turn is pivotally connected with the crank 30.

The link 46 is formed from a pair of separate link sections 46a and 46b disposed on opposite sides of the frame 10. The links 46 and 49 are pivotally connected by a pintle bar 50. This pintle bar has end portions 50a extending outwards and provided with pedals 51 upon which the feet may rest. The bolt 47 may be removed and the upper end of the link 46 shifted forwards or rearwards along the arm 45 and the bolt may be reconnected with one of the openings 48 to change the movement of the arm 45 and thus the amplitude of its oscillation. As the crank 30 rotates the links 49 and 46 will be reciprocated, which in turn oscillates the radial arm 45 and the handle bars 42.

A reciprocating massaging element 55 is mounted on the front of the frame 10. This massaging element includes a massaging head 55a which is mounted on a rod 56 slidably engaged through a bearing 57. The upper end of the bearing 57 is pivotally supported by a pintle 58 to the frame 10. The bottom end of the bearing 57 is supported by several bars 59 having slots 60 through which holding screws 61 pass. These holding screws are mounted on the frame 10. The screws 61 may be loosened and then the bearing 57 adjusted so that the rod 56 is vertical or inclined forwards to various degrees as desired.

The lower end of the rod 56 supports a pintle 62 which slidably engages in a slot 63 formed in a lever 64 which is pivotally mounted intermediate of its ends by a pintle 65 supported on a bracket 66 mounted on the frame 10. The rear end of the lever 64 is pivotally mounted on

the pintle rod 50. The arrangement is such that when the crank 30 operates, the link 49 will oscillate the lever 64. This causes the rod 56 to reciprocate. A person may lean against the massaging element to receive a massage.

A pair of riding stirrups 68 are removably mounted upon the sides of the seat 14. Each riding stirrup 68 is provided with a catch 69 at its top engageable with a bracket 70 mounted on the sides of the seat 14. Stationary pedals 72 are mounted on the rear of the frame 10 to facilitate mounting the seat 14.

The operation of the exercising horse is as follows:

A person sits on the seat 14 and engages his feet in the stirrups 68. Then he turns the switch 39 to start the motor 38 which indirectly causes the seat 14 to oscillate forwards and rearwards simulating a bucking broncho.

Another method of using the exercising device would be to rest the feet on the pedals 51 instead of engaging them in the stirrups 68. The handle bars 42 are also gripped. This operation varies the muscles which are being exercised. Attention is called to the fact that while the seat 14 oscillates the pedals 51 will simultaneously move through a certain cycle. The handle bars 42 will also oscillate.

Another way to use the exercising horse would be to sit on the seat 14 with both legs to one side of the seat and then set the seat 14 into oscillation.

The exercising horse may also be used by standing near it and gripping the handle bars 42 or seat 14 from various positions and wrestling with these parts during the operation of the exercising horse.

Many additional exercises may easily be worked out with this exercising horse. The massaging element 55 may be used merely by leaning or engaging portions of the body against it. In addition to the various oscillating movements of the exercising horse it is possible by means of the transmission 35 to control the speed of oscillation.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In a device of the class described, a frame, a long bearing pivotally mounted on said frame and adapted to slidably and non-pivotally support a rod of a massaging element, a rod for a massaging element slidably and non-pivotally mounted through said bearing, an oscillating lever having a slot extending in a direction which is approximately at right angles to said rod and radially of its point of oscillation, a pintle mounted on said rod and engaging in said slot by which oscillations of said lever will reciprocate said rod, whereby said bearing may be moved to various pivotally fixed positions to move said pintle along said slot while the direction of sliding of said rod is changed.

2. In a device of the class described, a frame, a long bearing pivotally mounted on said frame and adapted to slidably and non-pivotally support a rod of a massaging element, a rod for a massaging element slidably and non-pivotally

mounted through said bearing, an oscillating lever having a slot extending in a direction which is approximately at right angles to said rod and radially of its point of oscillation, a pintle mounted on said rod and engaging in said slot by which oscillations of said lever will reciprocate said rod, whereby said bearing may be moved to various pivotally fixed positions to move said pintle along said slot while the direc-

tion of sliding of said rod is changed, and means for holding said bearing in various pivotally fixed positions comprising a strip pivotally connected with said bearing and having a slot, and a fastening screw mounted on said frame and passing through said slot for clamping said strip in various positions.

MYLES JOHN BURKE.
